UNITED STATES PATENT OFFICE.

JOHN P. REINECKE, OF LORAIN, OHIO, ASSIGNOR TO THE HOFFMAN HEATER COMPANY, OF LORAIN, OHIO, A CORPORATION OF OHIO.

GAS BURNER.

Application filed July 18, 1924. Serial No. 726,819.

This invention relates to gas burners, and has for its object to provide an efficient burner in which back fire to the mixer is prevented by causing the gas to pass through the 5 wall of an inner perforated tube to an outer chamber surrounding the tube prior to its escape to the burner outlets.

Further objects of the invention are to provide a burner which can be economically 10 manufactured, which can be easily assembled or taken apart and to provide a mounting for the cover member and the perforated tube retained thereby by which the tube and cover member are accurately positioned 15 with respect to the body of the burner and by which the perforated tube is so held that it is free to expand longitudinally and will not be distorted by expansion due to heat.

With the above and other objects in view 20 the invention may be said to comprise the burner as illustrated in the accompanying drawings hereinafter described and particularly set forth in the appended claims, together with such variations and modifications thereof as will be apparent to one skilled in the art to which the invention 25 pertains.

Reference should be had to the accompanying drawings forming a part of this specification in which Fig. 1 is a side elevation of the burner with a portion of the head broken 30 away and shown in section; Fig. 2 is a view similar to Fig. 1 taken at right angles thereto; Fig. 3 is a bottom plan view of the cover 35 member; Fig. 4 is a top plan view of the burner; Fig. 5 is a top plan view of the body portion of the burner with the cover member and inner tube removed.

Referring to the accompanying drawings, 40 the burner consists of a tubular body 1 which may be in the form of a casting, the lower end of the body portion being enlarged to provide a mixing portion 2 into which projects the gas inlet 3 which is of smaller diameter than the end portion 2 of the gas burner 45 and which is connected thereto by a spider 4 to provide an annular air inlet surrounding the gas inlet 3.

At the upper end thereof the body of the 50 burner has a portion 5 of enlarged diameter, the lower end of which is connected to the body of the burner by an offset shoulder 6. Extending into the lower end of the 55 enlarged portion 5 is an annular flange 7 which forms an extension of the lower por-

tion of the burner body. On opposite sides the upper portion 5 of the body is flared outwardly to provide diametrically opposite channels 8 which gradually increase in depth toward the top of the burner. 60 Adjacent the top of the burner slotted attaching lugs 9 project outwardly from the channeled portions 8, the lugs 9 being formed with their top surfaces on a level with the upper edge of the body. The upper end of the 65 burner body has attached thereto a closure member 11 which has a peripheral shape corresponding substantially to the shape of the upper edge of the body and which is provided with slotted attaching lugs 12 70 which overlie the attaching lugs 9 of the body, the lower edges of the lugs 12 being offset upwardly from the underside of the closure member to provide positioning shoulders 13 which space the lugs 12 slightly from 75 the lugs 9 and form a seal to prevent escape of gas to the space between the lugs. To assist in accurately positioning the closure member and in holding the closure member against relative movement with respect to 80 the body portion the closure member has formed therein downwardly projecting lugs 14 which fit within the upper ends of the channels 8 in the body and bear against the bottom and sides thereof, the closure member 85 being detachably secured to the body member by means of bolts 15 engaging in the slots of the attaching flanges 9 and 12.

The closure member 11 is preferably hollowed out at the top to provide a lighter 90 construction and has around its periphery closely spaced notches 16 which extend in the direction of the axis of the burner and are of gradually increasing depth toward 95 their lower ends, the bottoms of the notches 16 at the bottom of the closure member lying inside the wall of the upper portion 5 of the burner, there being forming ports through which the gas escapes from the body of the burner. On its underside the 100 closure member 11 has an annular boss 17 which is of the same diameter as the flange 7 at the lower end of the enlarged portion 5 and which is axially aligned with said flange. A perforated tube 18 is secured between the bottom of the closure member 11 and the lower end of the enlarged portion 5 of the body, and this tube has its upper 105 end fitting upon the outside of the annular boss 17 and its lower end fitting upon the 110

2 outside of the flange 7. The flange 7 and boss 17 serve to rigidly hold the tube 18 centrally within the enlarged portion 5 and the tube 18 is of a length slightly less than 5 the distance between the underface of the closure member 11 and the lower end of the enlarged portion 5 so that it is capable of slight longitudinal movement upon the flange 7 and boss 17. The longitudinal play 10 of the tube 18 is sufficient to permit free longitudinal expansion of the tube when it becomes heated so that the tube will not be distorted if it becomes heated while in use.

15 Having described my invention, I claim—
1. A gas burner comprising a tubular head portion and a tubular body portion of smaller diameter communicating with the inner end of the head portion, an annular 20 flange within the head portion forming a continuation of said body portion, a closure member secured upon the outer end of said head portion said member having peripheral notches forming gas outlets, and said member having an inwardly projecting boss 25 upon its inner side, interfitting shoulders on said cover plate and head for positioning said boss in axial alignment with said annular flange, and a perforated tube within

the head portion, said tube having its opposite ends fitting upon said annular flange and boss respectively. 30

2. A gas burner comprising a tubular body enlarged at one end to provide a mixer portion and at its opposite end to provide 35 a head portion, an annular flange projecting into the inner end of the head portion, said flange forming a continuation of the passageway leading into the head, a closure member secured upon the outer end of the 40 head, said member having peripheral slots forming gas outlet openings, laterally extending attaching lugs formed upon the closure member and body, said lugs having interengaging shoulders to position the closure member on the head, securing means 45 cooperating with said lugs, an inwardly projecting boss on the inner side of the closure member in axial alignment with the annular flange, and a perforated tube having its ends fitting upon said flange and boss respectively, said tube having a slight longitudinal play on said boss and flange to allow for expansion and contraction. 50

In testimony whereof, I hereunto affix 55 my signature.

JOHN P. REINECKE.
